John J. Lynch

UNITED STATES PATENT OFFICE

HENRY CARDON, OF HILLSDALE, NEW JERSEY

SHELL LAMP

Application filed October 1, 1930. Serial No. 485,595.

This invention relates to lamps and in particular to shades for use in connection therewith which are made from natural sea shells.

A particular object of my invention is to provide a lamp of the character referred to which will bring out the natural beauty and coloring of the shells and provide a light diffusing medium for use as a shade which will be ornamental and will enhance the appearance of the lamp.

A further object of my invention is to provide in a lamp employing sea shells for a shade, means whereby the shells may be opened up for the replacement of the illuminating bulb.

A further object of my invention is to provide a bracket which may be secured to any standard lamp and which will permit the mounting of shells over any light bulb whether employed in connection with a wall bracket, drop light or lamp having a base for use on a desk or other article of furniture.

A still further and equally important object of my invention is the provision of a shade or shell holding bracket which may be made up at small cost so that shells of various sizes may be accommodated therein, and one which will not detract from the appearance of the shells; can be used for mounting the shells very close to the lamp socket, will accommodate shells of various sizes and formation and will hold the shells securely in position.

With these and other objects in view, my invention comprises the construction, combination and arrangement of the various parts hereinafter described, and then particularly pointed out in the appended claim.

In the drawing:

Figure 1 is a view in front elevation of a shell lamp constructed in accordance with my invention.

Figure 2 is a view in side elevation of the lamp as illustrated in Figure 1, the base portion thereof being omitted, the figure showing in outline the position of the shells when the same are opened up to permit removal or replacement of the light bulb.

Figure 3 is an enlarged section taken on

the line 3—3 of Figure 2 and shows the relative arrangement of the shell holding brackets or parts, and

Figure 4 is an enlarged section taken on the line 4—4 of Figure 1 and shows the method of pivotally supporting the shell from the clamping ring.

Referring to the drawing in detail, 5 indicates a lamp base of the usual form to which is connected the extension cord 6 and light plug 7. The lamp base may be ornamented in any suitable manner or, instead of a lamp base, my invention may be applied to a drop light, wall light or in any other light employing an electric bulb and socket.

The base 5 is provided with the socket 8 in which is disposed in the usual manner, the illuminating light bulb 9.

The shells employed in my construction are preferably of the scalloped type and delicately tinted so that the light diffused will be bright, yet subdued and the natural beauty of the shells will be brought out, thus providing a lamp that is highly ornamental. The shells are so paired that a small one 10 and a large one 11 are employed together so that the smaller one 10 fits within the larger one 11 to form a cover or receptacle for the light bulb 9 although this relative size of the shells is not necessary in order to bring out the effect desired. The shells in their natural state are provided with the extensions 12 which are flat and provide a place for fastening the bottom of the shells to the hinge bracket 13.

In view of the fact that the construction of the lamp is identical at both sides and for both shells, explanation of one side only will be given and referring particularly to Figures 3 and 4, it will be noted that the socket 8 holds the two halves 14 and 15 of a clamp ring construction, the parts being secured together through the medium of the holding screws 15—A. The construction of the ring 14 and its parts are identical to the construction of the ring 15 which is provided at its center with a hinge eye 16 in which is disposed a hinge pin 17.

To the extended inner face portions 12 of the shell is connected through the screws or

bolts 24, the hinge bracket 13 provided with depending sleeves 21 which fit about the hinge pin 17. This bracket has adjustably threaded therein the adjusting screw 19, the 5 head of which engages the bulb socket 8 to limit the swinging movement of the shell.

The bracket is formed to provide at its ends as at 25 and 26 inwardly bent hooks for holding the ends of tension springs 27 and 28.

10 The opposite ends of the springs are connected to the companion hooks of the hinge bracket at the opposite side of the lamp.

It will be noted that the ring 15 and bracket 13 are each punched from a single piece 15 of metal and the opposite ring portion 14 and its bracket are identically the same so that it is only necessary to manufacture two separate pieces and thus the cost of manufacturing the lamp is materially reduced.

20 The screws 15—A may be relatively adjusted so that deformed shells may be mounted in substantially parallel relation, and may be also adjusted relatively to the bulb and its support.

25 It is evident that the center of rotation of the shells is about the hinge pins 17 and the springs 27 and 28 being disposed above the point of rotation will tend to draw the shells together until they meet and in order to prevent their breaking when they do come into contact, use is made of the adjusting screws 19 which engages the socket and prevents the shells from coming into forcible contact with each other along their upper, scalloped edges.

30 35 It is evident that by adjusting the screws 19, the closing movement of each of the shells may be adjusted independently.

It is evident also that any type of shell 40 may be employed and the shells against the action of the springs 28 and 27 may be opened up to the position shown in outline in Figure 2 to permit removal or replacement of the bulb 9.

45 It is evident, therefore, that I have provided a unique shell lamp construction which permits of attachment to any type of lamp, the shell shade which diffuses the light and displays the natural beauty of the shell.

50 My invention is not to be restricted to the precise details of construction shown since various changes and modifications may be made therein without departing from the scope of the invention or sacrificing the advantages derived from its use.

55 What I claim is:—

60 The combination with a lamp comprising a light bulb support, of separable, semi-circular clamp rings arranged to be positioned about said support, means for securing the clamp rings together, an upstanding hinge eye formed on each of said rings, a hinge pin in each of the eyes, a bracket pivoted on each of said pins, a decorative translucent shade on each of said brackets, one of said shades 65 fitting partly within the other shade to sub-

stantially conceal said light bulb, ears on said brackets, and springs connecting the brackets of opposite sides to draw the shades toward each other and a screw in each of the brackets for engaging the bulb support for limiting the movement of the shades toward each other.

In testimony whereof I affix my signature.

HENRY CARDON.
